UNITED STATES PATENT OFFICE.

EDWARD LAAS, OF SHAWNEE, OKLAHOMA, AND HIRAM H. SPONENBURG, OF GURNEE, ILLINOIS, ASSIGNORS TO LAAS & SPONENBURG CO., A CORPORATION OF ILLINOIS.

RAILWAY-TRACK DEVICE.

1,077,353.

Specification of Letters Patent.

Patented Nov. 4, 1913.

Application filed April 14, 1913. Serial No. 760,975.

To all whom it may concern:

Be it known that we, EDWARD LAAS and HIRAM H. SPONENBURG, citizens of the United States, residing at Shawnee, in the county of 5 Pottawatomie and State of Oklahoma, and Gurnee, in the county of Lake and State of Illinois, respectively, have invented certain new and useful Improvements in Railway-Track Devices, of which the following 10 is a specification.

Our invention relates to a railway track device which serves the purpose both of a tie plate and a rail brace, and the invention has for its principal object to provide a 15 novel device of this sort which will permit the rail to be raised or "shimmed up" without removing the device from the tie or without disturbing the spikes or other attaching means employed for securing it in 20 place on the tie, and which, when the rail is "shimmed up," will afford the support necessary for holding the shims in position and for holding the rail from lateral displacement or spreading due to the thrust of 25 the car wheels.

It is well known that the rails of a railroad which is not stone or cinder ballasted have to be raised or "shimmed up" from the ties periodically at certain places along the 30 road bed because of the heaving and disturbance of the ballast and subsoil due to the frost. As it is not feasible to raise the cross ties on which the rails are supported, the usual method followed when the rails of a 35 track have to be leveled up is to place wooden shims between the rails and the ties. This "shimming up" of railroad rails is the cause of frequent accidents as it has not been possible to give the rail as secure a position 40 on the shims as it had upon the ties. For example, the ordinary rail tie plates and braces cannot be used when a rail is shimmed up. The shims do not afford a firm enough support to make a rail brace of any value 45 and if a tie plate is used, of any of the types commonly employed, the ribs or wedges which, by embedding themselves in the tie 50 keep the tie plate in position, will split the relatively thin, light shims. Moreover, it is 55 essential that a tie plate be firmly spiked to the tie. If the tie be raised upon shims it cannot be securely attached in position. Our invention seeks to remedy this difficulty by providing a tie plate which is furnished 60 with means for preventing the lateral dis-

placement or spread of the rail, which does not have to be removed when the tie is shimmed up and which is furnished with means for preventing the lateral displacement of the rail in its shimmed up position 60 as well as in its normal position. The device has, therefore, the important advantage of minimizing the danger of railroad accidents due to the shimming up of rails from their seats on the cross ties, and also the subsidiary but important advantage of facilitating the work of the track crew. Moreover, as the tie plate of our invention does not have to be periodically removed and replaced, the life of the tie is prolonged and 70 the possibility of accident due to the looseness of the tie plate on the tie is eliminated.

It is well known that tie plates have a tendency to bend up along the edge of the rail. This bending of plates occurs much 75 more frequently along the outside edge of the rail base than at the inside edge, for the reason that the thrust of the wheels is outwardly. To overcome the tendency to bend along the outside edge of the rail base without waste of material, which commercially is a very important consideration in devices of this sort, the tie plate of our invention has a tapered configuration, being relatively wide at the place where the outside edge of 80 the rail base bears against it, and tapering in width inwardly.

The invention is illustrated, in certain preferred embodiments, in the accompanying drawings, wherein—

Figure 1 is a side elevation of one form of our invention, the rail being shown in section; Fig. 2, a plan view of the device shown in Fig. 1; Fig. 3, a view similar to Fig. 1 of a modified construction, and Fig. 90 4, a plan view of this modification.

Like characters of reference designate like parts in the several figures of the drawings.

Referring to the drawings, A designates a railway rail and B one of the cross ties supporting the same.

The device of our invention shown in Figs. 1 and 2, consists of a plate C, which is preferably widest along the outer edge of the rail base and tapers in width inwardly, provided with an integrally formed upright member D which is preferably strengthened by the reinforcing web E. The upright member D is formed with a vertical, flat surface d parallel with the axis of the rail 105 110

against which the outer edge of the base of the rail may abut at different altitudes. Preferably the upright member D is formed with a substantially horizontal member F which, by bearing against the vertical web of the rail, assists in preventing the spread or tilting of said rail. The inner edge of the plate C is formed with a spike hole G and the outer edge with two spike holes H, the spikes, designated I in the drawings, overlapping the edges of the rail base in the usual manner. Preferably the projection J at the outer edge of the plate, which the upright member D and its supporting web E rise from, is formed at its outer extremity with a spike hole K. The rail, under normal conditions, rests directly upon the tie plate. If the rail has to be raised any suitable number of shims, L, may be interposed between the plate and the rail base. In either position the outer edge of the rail base bears against the surface d. It will be seen that in shimming up the rail the position of the tie plate on the tie is not disturbed nor is the spike which passes through the spike hole K. The other spikes simply have to be withdrawn sufficiently to permit the rail to be raised the required amount.

In Figs. 3 and 4 we have shown a two-part plate, the inner member of which is provided with a shoulder or abutment against which the inner edge of the rail bears when in its normal position, and which serves to keep the shims from displacement when the rail is shimmed up. M designates the outer plate and N the inner plate, said plates being formed on their meeting edges with projections m, n, each of which enters a correspondingly formed recess in the edge of the other plate. The plate M is formed with an upright member O provided, preferably, with a horizontal member P adapted to bear against the vertical web of the rail. The plate N is formed with a projection or shoulder Q, the inside face q of which is vertical and serves to retain in place the shims L when the rail is shimmed up. When the rail is in its normal position the edge of the base flange bears against this shoulder. The plate N is preferably formed at its extremity

with a spike hole R in addition to spike holes S along the edge of the rail base. The plate M is preferably formed with spike holes, designated T, similar in their arrangement to the spike holes of the other form of device. 55

We claim:

1. A track device of the character described, comprising a plate adapted to extend under the base of a rail and be secured to one of the supporting ties thereof, provided with an upright member having a vertical surface parallel with the edge of the base of the rail, against which surface said edge is adapted to bear when resting on said plate and also when shimmed up therefrom, 60 and a substantially horizontal member projecting from said upright member which bears against the vertical web of the rail.

2. A track device of the character described, comprising co-engaging plates adapted to extend under the base of a rail and to be secured to one of the supporting ties thereof, one of said plates being formed with an upright member having a vertical surface against which one edge of the base 75 of the rail is adapted to bear, and formed with a substantially horizontal member which bears against the vertical web of the rail, the other plate provided with an abutment, having a vertical face in line with the 80 opposite edge of the base of said rail.

3. A track device of the character described, comprising co-engaging plates adapted to extend under the base of a rail and to be secured to one of the supporting ties thereof, each plate having a projection adapted to enter a similarly formed recess in the meeting edge of the other plate, one 85 of said plates being formed with an upright member having a vertical surface against 90 which one edge of the base of the rail is adapted to bear at different altitudes, and the other provided with an abutment, having a vertical face in line with the opposite edge of the base of said rail.

EDWARD LAAS.
